UNITED STATES PATENT OFFICE.

FERDINAND W. KROGH, OF SAN FRANCISCO, CALIFORNIA.

DAVIT-FALL ATTACHMENT.

1,165,183.

Specification of Letters Patent. Patented Dec. 21, 1915.

Application filed January 16, 1915. Serial No. 2,577.

To all whom it may concern:

Be it known that I, FERDINAND W. KROGH, of San Francisco, California, have invented certain new and useful Improvements in Davit-Fall Attachments; whereof the following is a specification.

This invention relates to devices for releasing boats from the davit-falls whereby the boats may be released quickly and easily without danger to the man releasing them and without danger of the boat being released at one end and not at the other.

To the above ends I make use of two hooks at each end of the boat, one hook connected to the boat and the other to the davit-fall and between these hooks I employ a roller which may be toothed if desired, to engage teeth on the hooks, which roller is under control of the operator so that it may be rotated to disengage the hooks from each other or prevented from rotation to insure their continued engagement.

In the accompanying two sheets of drawings I have illustrated my device in its best form and will now proceed to describe the same.

In the drawings: Figure 1 is a side elevation of a boat as it hangs suspended from the davits, showing the lower ends of the falls and my invention applied thereto. Fig. 2 is a side elevation of a central standard for supporting the controlling and operating parts of the device. Fig. 3 is a central sectional elevation taken on the line 3, 3 of Fig. 2, looking in the direction of the arrows. Fig. 4 is an elevation of the connecting device between the davit-fall and the boat, but with the journal bearing of the standard, attached to the end of the boat, shown in section, and with a portion of the lower hook broken away to expose the controlling roller. Fig. 5 is a view at right angles to Fig. 4, showing the same parts but partly broken away in sections to show the controlling roller between the two hooks.

In these figures, 1 represents a boat and 2 the lower ends of the falls by which it is suspended from the davits, 3 being the blocks which may be provided with the usual hooks 4, or some other form of connection.

5 is a hook provided with an eye, 6, by which it is hung upon the hook 4, and having its hook portion, 7, approximately straight and provided with a series of notches, 8, which constitute, virtually, gear teeth. 9 is a companion hook provided also

with a straight portion 10, having notched teeth 11, and provided with a hook, 12, adapted to engage the eye bolt, 13, of the boat. The hook 12, may, if desired, be provided with a snap spring, 14, to prevent disengagement of the eye bolt, 13, and similarly the hook, 4, may be provided with a snap spring, 15.

16 is a roller provided with teeth, 17, to engage the teeth or notches, 8 and 11, upon the hooks, 5 and 9. The roller, 16, is controlled by means of a shaft, 18. This shaft extends longitudinally of the boat to any convenient point where it meets a similar shaft coming from the device at the opposite end of the boat. At this point the ends of the shafts are squared as at 19 and inserted into a coupling block 20. The coupling block is mounted between two standards, 21, in which the shafts have bearings, as seen in Fig. 3. These standards are mounted upon a seat of the boat, 22, or other convenient part of the boat.

An arm, 23, extends downward from the coupling block 20, and near its lower end there is pivoted a lever, 24, the pivotal point of which, 25, is above the end of the arm 23. The end of the lever, 24, is offset as shown in Fig. 2, to engage its pivot, and the side of the lever engages the end of the arm 23, as seen in that figure, whereby movement of the lever in the direction indicated by the arrow will swing the arm and turn the block 20, and the two shafts 18. This movement will turn the rollers, 16, and cause them to roll the companion hooks, 5 and 9, out of engaging position, thus releasing the boat, 1, from the falls. The final act of this disengagement as the ends of the hooks, 5 and 9, come beyond the center line of the rollers, 16, is likely to give the rollers, and through them, the shafts, the block 20, and the arm 23, a sudden throw, which might injure the operator if the lever, 24, were firmly fastened to the said arm, but, being pivoted as shown, the arm, 23, can throw in the direction indicated by the arrow in Fig. 2, without throwing the lever with it and therefore the operator is preserved from injury.

At 26 is a cross bar from one of the standards, 21, to the other, which cross bar supports two little brackets, 27, between which the arm, 23, is received, in its normal holding position. When in this position a pin, 28, is passed through holes in the

brackets and in the arm, thus locking the latter and preventing accidental disengagement of the boat.

In operation the boat may be swung outward from the side of a vessel and lowered by means of the falls in the usual manner until it reaches a proper point for its release. At this point the man in the boat, sitting near the standards, 21, grasps the end of 10 the lever, 24, pulls out the pin, 28, and swings the lever in the direction of the arrow shown in Fig. 2. This rotates the rollers, 16, and thereby disengages the companion hooks, 5 and 9, at both ends of the 15 boat at the same time, so that the boat is received squarely in the water without any danger of one end falling first and spilling out its contents.

29 is a stop for arm, 23; it acts also as a 20 brace for the standards, 21.

By way of supporting shafts, 18, after the boat is released from the falls, standards 30, shown in Fig. 1, may be applied at each end of the boat, if desired.

25 31 are flanges at each side of the rollers, 16, designed to prevent its lateral displacement.

Having thus described my invention, and an embodiment of it, in the full, clear and 30 exact terms required by law, and knowing that it comprises novel, useful and valuable improvements in the art to which it pertains, I here state that I do not wish to be limited to the precise construction and arrangement 35 of the several parts, as herein set forth, as the same may be variously modified by a skilled mechanic without departing from the spirit of the invention.

What I claim and desire to secure by 40 Letters Patent of the United States is the following, to wit:

1. A davit-fall attachment comprising companion hooks engaged together and means between said hooks to release said engagement, one of said hooks being secured to the fall and the other to the boat.

2. A davit-fall attachment comprising companion hooks having a roller interposed between said hooks and means for controlling said roller.

3. A davit-fall attachment comprising companion hooks provided with teeth upon their engaging faces and a toothed roller

between said faces and engaging said teeth and means for controlling said roller.

55

4. A davit-fall attachment comprising companion hooks, one connected to the fall and the other to the boat, a roller interposed between the engaging faces of said hooks, a shaft connected to said roller and means for 60 operating said shaft and thereby rotating the roller to disengage the hooks.

5. A davit-fall attachment comprising companion hooks, one connected to the fall and the other to the boat, a roller interposed 65 between the engaging faces of said hooks, a shaft connected to said roller and a lever for turning said shaft and thereby rotating the roller to disengage the hooks.

6. A davit-fall attachment comprising 70 companion hooks in pairs at each end of a boat, rollers between the engaging faces of each pair of hooks, shafts extending from said rollers toward the middle of the boat to a meeting point, a coupling block connecting the meeting ends of said shafts, means for locking said shafts against rotation and means for rotating both shafts when unlocked, whereby both ends of the 75 boat are released from the falls simultaneously.

7. A davit-fall attachment comprising 80 companion hooks arranged in pairs at each end of the boat, means between said hooks for effecting the disengagement thereof, an arm for effecting the operation of said means, an offset lever pivoted to said arm, whereby the arm may be thrown in operative direction by the lever but the lever will 85 be free in the opposite direction.

90 8. A davit-fall attachment comprising companion hooks, one connected to the fall and the other to the boat, a roller interposed between the engaging faces of said hooks, a shaft connected to said roller and means for 95 operating said shaft, thereby rotating the roller to disengage the hooks and means for supporting said shaft lengthwise.

In testimony that I claim the foregoing I have hereto set my hand this 9th day of 100 January, 1915, in the presence of witnesses.

FERDINAND W. KROGH.
